UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,252,586.

Specification of Letters Patent.

Patented Jan. 8, 1918.

Application filed January 30, 1915. Serial No. 5,248.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

This invention relates to electric switches.

One of the objects of the invention is to provide an improved snap switch mechanism comprising a minimum number of parts 15 capable of cheap manufacture and ready assembly.

Other objects and advantages of the invention will appear hereinafter in connection with a description of the accompanying 20 drawing wherein—

Figure 1 is an elevational view of a switch mechanism.

Fig. 2 is a sectional view of the same incorporated in a battery switch device.

Fig. 3 is an enlarged perspective view 25 of a switch mechanism part.

Fig. 4 is an enlarged perspective view of one of the movable switch contacts.

Fig. 5 is a plan view of a modified form 30 of switch mechanism.

Fig. 6 is a sectional view of one device to which the mechanism of Fig. 5 may be applied, and

Fig. 7 is a plan view of a base showing 35 the conducting parts thereon associated with the switch mechanism.

The switch mechanism illustrated comprises, in general, a pair of spaced pivoted contacts 1, an operating member having a 40 part disposed between said contacts and reciprocable in engagement therewith across the plane of the axes thereof and energy storing means 2 associated with the parts to effect a snap oscillation of the contacts 45 as the switch actuating part passes in either direction across the contact axes.

Referring more specifically to the drawing, there is shown in Fig. 1 a pair of contact members 1 medially pivoted on the 50 adjacent ends of a looped spring 2, said spring being carried by a supporting plate 3 and insulated therefrom by suitable means such as a hollow rivet or sleeve 4 and an insulating bushing 5. A push and pull

switch operating member 6 extends through 55 the sleeve 4 and is also carried by the plate 3. Said operating member carries on its inner end an insulating block 7 beveled or otherwise shaped to provide opposite knife edges 8 against which the contacts 1 are 60 pressed by the looped spring 2. In practice, the contacts 1 are loosely mounted on lugs 2^a of the spring 2 and are held in position thereon by the resiliency of said spring which forces the contacts against the 65 block 7. Thus assembly of these parts is facilitated. The operating member is normally in extreme position where the block 7 rests at one side of the plane of the pivotal axes of the contacts, so that the spring 70 2 normally holds the contacts with their active faces 9 either biased apart or biased together.

Assuming the mechanism to be in closed circuit position as shown in Fig. 1, elevation of the push button 6 forces the block 7 over the adjacent faces of the contact 1 which are bodily repressed against the action of the loop spring 2. The free extremities 9 of the contacts are, however, 75 maintained unmoved until the knife edges 8 of the block cross the plane of the contact pivots, whereupon the contacts are oscillated with a snap movement by the energy stored in spring 2 and the contacts thus assume a 80 reverse obliqueness with the ends 9 closely adjacent. Operation of the mechanism in the other direction effects a snap make of circuit in a similar manner. In practice, the extremities 9 of the movable contacts are 85 reflexed as shown to increase the resiliency thereof and the opposite ends 16 of the contacts are bent apart at substantially right angles to engage the spring 2 and limit oscillation of the contacts when circuit is opened. 90

The mechanism described is applied in Fig. 2 to a battery switch device. As there shown an insulating base 10 is provided with a pair of spaced contacts 11 projecting through the base and having binding post 100 connections 12 on the outer side thereof. A tubular casing 13 is seated on the base and incloses the parts of the switch mechanism. A pair of screws 14 extend through opposite ends of the base 10 and take into the front 105 plate 3 for securing said base and plate together and clamping the casing 13 therebetween. The stationary contacts 11 carried

by the base are also brought into registry with the movable contacts 1 when the base and plate are thus connected. A conventional face plate 15 is attached to the plate 3 when the device is installed.

The modified form of switch mechanism shown in Fig. 5 is designed for a push button operated lamp socket. In this embodiment a pair of movable contacts 17 are pivoted in spaced relation on terminal plates 18 secured to an insulating base 19. A push button switch operating member 20 of insulating material extends across the base 19 between the contacts 17 and has fixed thereto a pair of resilient spring fingers 21 having convexed extremities 22 confined between the contacts and movable thereover from one side to the other of the contact axes. Operation of this mechanism is in general similar to the operation of the mechanism shown in Fig. 1. In this embodiment, however, the energy storing means is in the form of the resilient fingers 21 and thus directly associated with the operating member rather than with the contacts. Said spring fingers 21 are under tension at all times, but the tension thereof is augmented as the push button is moved in either direction from extreme position until the knife edges 22 pass the plane of the axes of the contacts 17 whereupon said contacts are oscillated with a snap movement to make or break circuit between the terminal plates 18 and stationary contacts 23 and 24 carried by the base. As shown the contact 23 is connected with a lamp shell 25 and the contact 24 is connected with a center contact 26, so that the switch controls both sides of the line supplying the translating device.

The socket base 19 carries the screw shell 25 on its lower face and the switch mechanism on its upper face. A second insulating base 27 is provided to cover the switch mechanism and is attached to the base 19 by screws 28 and the terminal plates 18. Any suitable casing may be provided to inclose the socket parts. As shown the casing for this purpose comprises a cylindrical shell 29 and a dome shaped cap 30 therefor.

In both forms of the device illustrated the switch mechanism comprises a minimum number of parts which are assembled to constitute two units capable of ready association. Furthermore, the various parts are of sturdy construction capable of resisting severe service and not likely to become disordered. While the mechanisms are also very compact, it is to be noted that the current conducting elements thereof are thoroughly insulated to eliminate all liability of short circuiting.

What I claim as new and desire to secure by Letters Patent is:—

1. In an electric switch, in combination, 65 a pair of oscillatable contacts pivoted me-

dially, an operating member having a part reciprocable between said contacts from one side to the other of the plane of the axes thereof and energy storing means constituting a support for said contacts.

70

2. In an electric switch, in combination, a pair of oscillatable contacts pivoted medially, a reciprocable operating member arranged between said contacts and having parts in engagement therewith and movable thereover and means to receive energy during initial movement of said operating member and to expend such energy by oscillating said contacts as said operating parts pass the pivotal axis thereof, said energy storing means constituting a support for said contacts.

75

3. In an electric switch, in combination, a resilient member, a pair of operated contact members pivoted medially thereon, contacts adapted for engagement by said operated members, a reciprocable operating member between said members and movable thereover from one side to the other of the axis thereof, said resilient member being 80 associated with one of said members to bias together the ends of said operating members on the side of the axis away from said operating member.

85

4. In an electric switch, in combination, 95 a resilient member, an operated member pivoted medially thereon, a contact adapted for engagement by said operated member, a reciprocable operating member having a knife edge bearing upon said operated member and movable thereover across the plane of the axis thereof, said resilient member being associated with certain of said members for biasing said operated member toward said operating member and effecting a quick oscillation of said operated member as said knife edge crosses the plane of the axis thereof.

100

5. In an electric switch, in combination, a pair of spaced operated members pivoted 110 medially and having associated contacts, a reciprocable member therebetween and having knife edges movable thereover across the plane of the axes thereof, and normally tensioned resilient means associated with certain of said members biasing the adjacent ends of said operated members in opposite directions and in accordance with the position of said knife edges with respect to said axes.

115

6. In an electric switch, in combination, a pair of spaced operated members pivoted medially and having associated contacts, a reciprocable member therebetween and having knife edges movable thereover across the 125 plane of the axes thereof, and normally tensioned resilient means associated with certain of said members biasing the adjacent ends of said operated members in opposite directions and changing the direction of 130

bias thereof with a snap movement as said knife edges cross the plane of said axes.

7. In an electric switch, in combination, an oscillatable operated member, a support therefor, and common means to operate said member and to hold the same in assembled relation with said support.

8. In an electric switch, in combination, a spring, an oscillatable operated member 10 loosely mounted thereon, and a reciprocable member to operate said oscillatable member and to maintain the same in assembled relation with said spring.

9. In an electric switch, in combination, a 15 resilient support, an oscillatable operated member medially pivoted thereon, and common means to operate said member and to

maintain the same in its pivotal assembly upon said support.

10. In an electric switch, in combination, 20 an energy storing supporting means, an oscillatable contact medially and loosely pivoted thereon, a coöperating contact for said oscillatable contact, and a reciprocable member to operate said oscillatable contact and 25 to maintain the same in its pivotal relation with said energy storing means.

In witness whereof, I have hereunto subscribed my name in the presence of two witnesses.

CHARLES J. KLEIN.
